(No Model.)

F. W. STAMMLER.
ROLLING MILL.

No. 375,657.

Patented Dec. 27, 1887.

WITNESSES,

Abs. Hamilton Jr.
James Cranston

INVENTOR.

Fred W. Stammer

UNITED STATES PATENT OFFICE.

FRED W. STAMMLER, OF JOHNSTOWN, PENNSYLVANIA, ASSIGNOR TO THE CAMBRIA IRON COMPANY, OF PENNSYLVANIA.

ROLLING-MILL.

SPECIFICATION forming part of Letters Patent No. 375,657, dated December 27, 1887.

Application filed November 23, 1887. Serial No. 255,971. (No model.)

To all whom it may concern:

Be it known that I, FRED W. STAMMLER, a citizen of the United States, residing at Johnstown, in the county of Cambria and 5 State of Pennsylvania, have invented certain new and useful Improvements in Rolling-Mills; and I do hereby declare the following to be a full, clear, and exact description of the same, such as will enable others skilled in the art to 10 which it appertains to make and use the same.

My invention relates to mechanism for handling the piece of metal being rolled and transporting it successively from pass to pass of the rolls of a three-high train, as will be 15 hereinafter fully described.

My invention consists in rising and falling feed-tables and means for operating them; and the main object of my invention is to greatly 20 simplify the mechanism used to operate these tables.

Referring to the sheet of drawings which is annexed to this specification and forms part of it, Figure 1 represents a longitudinal vertical section on the line A B C D E F of Fig. 2. 25 Fig. 2 represents a transverse vertical section on the line G H of Fig. 1.

In the description which will follow like characters of reference will refer to like parts throughout.

1 represents an ordinary stand of three-high rolls, which need no description, except that they are designed to revolve in the directions indicated by the arrows.

2 and 3 are the feed-tables, upon which are 35 supported the feed-rollers 4.

5 are paired rock-arms of equal length. Each of the rock-arms are separately pivoted to tables 2 and 3 at 6, the other end of the rock-arms 5 being attached in pairs to the 40 rock-shafts 7, one of the pair being attached to each end thereof. Near the centers of each of the rock-shafts 7 is attached another rock-arm, 8, the other end of the rock-arm 8 being pivoted at 9 to one and the same long connecting-link 10. The link 10, for convenience of manufacture and transportation, may be made in parts and connected as shown at 11, Fig. 1, or, to avoid bifurcating levers 8, the link 10 may be made as twin links, as shown

in Fig. 2. However, it performs its function 50 as a complete and united bar.

12 is a bifurcated link, one end of which is pivoted to the pivot 9 of one of the rock-arms 8, and the other end of which is pivoted at 13 to the cross-head of a hydraulic or steam motor, 14. The lengths of rock-arms 8 are equal 55 each to each, and the distance between the supporting ends of any two is equal to the distance between their swinging ends. They therefore are maintained parallel in all positions. Likewise the rock-arms 5 are parallel to each other in all positions; and, as they are of equal lengths each to each, the rising and falling tables are always maintained parallel to all positions of themselves, and as the first 60 position shown in full lines is a horizontal one, it follows that the tables 2 and 3 will always be horizontal, no matter how much they may be raised.

If pressure be applied to the motor 14, so as 70 to move it so that its cross-head occupies the dotted position, then will all other parts of the mechanism occupy their dotted position. The full lines represent the extreme lower position, and the dotted lines the extreme upper position, of the rising and falling tables 2 and 3.

It will also be understood from the foregoing description that tables 2 and 3 rise together and fall together, so that they always 75 lie in the same horizontal plane.

It will be seen that table 2 is closer to the rolls in its lower position, this being the result of the location of the rock-shafts 7 below the level of the pivots 6, and the consequent angularity of the rock-arms 5. Likewise it 80 will be seen, and for the same reason, that table 3 is closer to the rolls in its upper position. From the direction of revolution of the rolls it is manifest that the lower position of table 2 is its feeding-in position; also that the upper position of table 3 is its feeding-in position. Therefore both tables are closer to the rolls in their feeding-in positions.

15 is an idle-roller journaled in brackets attached to the housing of the stand of rolls 1, 90 the office of this roller being to bridge over the space between the rolls and table 2 when table 2 is in its feeding-out or receiving position.

Likewise 16 is a roller similarly supported and to perform a like office in connection with table 3. Feed-rollers 4 are driven by any suitable system of gearing.

5 17 represents castings which form the bearings for rock-shafts 7, 18 being a shield fitted to casting 17 to keep the scale from the working parts of the mechanism, as clearly shown in the drawings.

10 Having described the several parts of my invention, I will now, for further clearness, explain the working thereof.

The tables 2 and 3 being in their lower position, a hot bloom is deposited on table 2.

15 The feed-rollers 4 are then actuated to feed it into the rolls, emerging from which it is received on table 3, roller 16 supporting it in its passage from the rolls to said table 3. The motor 14 being put into action, the tables, 20 through the described mechanism, are raised to their upper position, table 3 thereby approaching the rolls and table 2 receding from them. The rollers 4 are now actuated to feed the piece being acted upon into the rolls, 25 emerging from which it passes over the supporting-roller 15, and is received on table 2. The tables are then lowered and the operation repeated. Suitable push-over devices are used to move the piece being rolled sidewise from 30 pass to pass; but as they form no part of this invention, they are neither illustrated nor described. Automatic rolling-mills, as heretofore constructed, are much too complicated to be successful, the great cost of maintaining a 35 complicated system of mechanism, when exposed to the action of water and roll-scale, more than overbalancing the advantages to be derived from them, and much destructible mechanism is comparatively inaccessible in 40 deep pits and much exposed to falling scale. Sliding parts are also used in this connection, which, from their working condition, are hard to lubricate and protect from damaging wear; but by discarding slides and reducing the lever system to its simplest form, I am enabled 45 to shield the wearing parts from scale and also to use a shallow pit, and the actual wearing parts in the pit are reduced to five pivoted connections, and the pressure on the sides of these 50 pivots is always in the same direction.

In rolling-mills with rising and falling tables it is found desirable to have the piece being rolled pass over a rigidly-supported roller as it emerges from the rolls, for the rolled piece 55 sometimes becomes bent down at the advancing end, and as the piece is forcibly expelled from the rolls this bent end, striking movable mechanism, is very destructive to it; but the objection to using such rigidly-supported roller 60 in rolling-mills as heretofore constructed, in which the tables were at the same distance from the rolls while receiving as when feeding in, has been that too much space intervened between the rolls and the feeding-tables when 65 in their feeding-in position, thereby necessitating an intervening roller, which, if an idle roller, cannot assist to enter the piece being

rolled into the rolls, and, if a constantly-driven roller, it resists drawing back the piece being rolled, in order to project it again against the rolls if they should from any cause fail to bite the first time. All of these objections I am able to avoid by having the tables move so that they will be closer to the rolls when in their feeding-in position than when in their 75 receiving position. Another advantage I gain by this movement is that I thereby use shorter tables, for if a short table is close to the rolls while receiving the piece being rolled, the velocity at which the piece is expelled from the 80 rolls is sufficient to throw the piece clear over the table onto the floor, even though the feed-rollers be stationary or revolved against the expelled piece.

It is obvious that minor changes may be 85 made in this described mechanism. The rock-arm 8 may be made in pairs, as twin arms, and may be continuations of rock-arms 5, or only one rising and falling table, such as is described, may be used, some other form being 90 used on the other side of the rolls. I therefore do not restrict myself to the exact construction described herein; but

What I claim as my invention, and desire to secure by Letters Patent, is—

1. The combination of a stand of three-high rolls, rising and falling feed-tables, and rock-arms pivoted directly to the rising and falling table to actuate and guide the same without any intermediate links or connections, substantially as and for the purpose set forth.

2. The combination of a stand of three-high rolls and rising and falling horizontal feed-tables which approach the rolls while moving to their feeding-in position and recede from 105 the rolls while moving to their receiving position, substantially as and for the purpose set forth.

3. The combination of a stand of three-high rolls, a rising and falling feed-table, paired 110 rock-arms pivoted directly to the said rising and falling feed-table, rock-shafts having attached to each end one of each pair of rock-arms, a second set of rock-arms attached, one each, to the aforesaid rock-shafts, the swing- 115 ing end of these last-mentioned rock-arms being attached through connecting mechanism to the same motor, substantially as and for the purpose set forth.

4. The combination of a stand of three-high 120 rolls with a rising and falling feed-table pivotally supported on rock-arms which are attached to rock-shafts, the pivoted ends of the said rock-arms being at all times above the horizontal plane passing through the rock- 125 shafts, substantially as and for the purpose set forth.

In testimony whereof I affix my signature in presence of two witnesses.

FRED W. STAMMLER.
